6767X

B. MYERS.

Millstone Dress.

Patented Sept. 28, 1831.

Benjamin Myers Chambersburg, Penn.

6767X

Collins Patent

The following is recited in these Collins' Patent and making part of the same, containing a description of the novel device Benjamin Myers invented, his improvement in the mode of Constructing Mill-Stones for Grinding grain, having been filed, etc.

Benjamin Myers of Chambersburg in the County of Franklin and State of Pennsylvania has made a new and useful improvement in the Construction of Mill-Stones, which is described as follows:

The runner is made of stone or other suitable material, and is shaped semicircular concavely. It is about twelve inches at the bottom and slopes gradually upwards, some inches at an angle of about fifty five degrees from this point it slopes to the apex at an angle of about thirty degrees.

The Bed Stone is composed of the stone mentioned at the runner above, six and a half feet in diameter, and fourteen inches thick. It is concave, and in shape corresponding to that of the runner, having an opening or eye in its centre about six inches in diameter through which the grain or other material to be ground is admitted. The Bed Stone is placed above the runner in the frame of the mill in the usual manner. The runner is secured to the spindle and turns concentrically and is graduated to the usual manner. Both Bed Stone and runner may be covered with sheet iron painted so as to form projections on their outer surfaces. If they may have parts convex in their circumference with their points projecting a sufficient distance, the runner outer surfaces, may be rendered rough for holding stones used in my concurrent invention. This however I do not claim as my invention it having been known before.

The whole of claim is my invention and wish to secure by Letters Patent in the form of the Bed Stone and runner as before described.
